UNITED STATES PATENT OFFICE.

EDWIN EARL EDGAR, OF TROY, OHIO, ASSIGNOR TO THE HOBART ELECTRIC MANUFACTURING COMPANY, OF TROY, OHIO, A CORPORATION OF OHIO.

DESIGN FOR A HOPPER FOR COFFEE-MILLS AND THE LIKE.

43,865.

Specification for Design.

Patented Apr. 22, 1913.

Application filed February 12, 1912. Serial No. 677,253. Term of patent 14 years.

To all whom it may concern:

Be it known that I, EDWIN EARL EDGAR, a citizen of the United States, residing at Troy, in the county of Miami and State of Ohio, have invented a new, original, and ornamental Design for Hoppers for Coffee-Mills and the Like, of which the following is a specification, reference being had to the accompanying drawing, forming part thereof.

Figure 1 is a perspective view of a hopper showing my new design, with the coffee

mill to which it is applied outlined in dotted lines, to show the relation of the parts. Fig. 2 is a top plan view of the hopper.

I claim:

The ornamental design for a hopper for coffee mills and the like, as shown.

EDWIN EARL EDGAR.
